UNITED STATES PATENT OFFICE.

NAZAIRES THERIAULT, OF RUMFORD, MAINE.

CURTAIN AND WINDOW-SHADE BRACKET.

1,316,750.

Specification of Letters Patent. Patented Sept. 23, 1919.

Application filed March 28, 1919. Serial No. 285,778.

To all whom it may concern:

Be it known that I, NAZAIRES THERIAULT, a citizen of the United States, residing at Rumford, in the county of Oxford and State of Maine, have invented certain new and useful Improvements in Curtain and Window-Shade Brackets, of which the following is a specification.

This invention has for its object the provision of a bracket for supporting window shades and curtains which may be attached to any window frame without the use of screws, nails, or other pointed fastenings. A further object of the invention is to provide a curtain and shade bracket which may be readily adjusted to the width of the window frame and by which the window shade and a pair of curtains may be easily hung in place and by which a valance or an overhanging pair of curtains may be supported when desired. The invention also seeks to provide a device in which the several parts will be so arranged as to not detract from the sightliness of the window and the hanging. The several stated objects and other objects which will incidentally appear in the course of the following description are attained in such a device as is illustrated in the accompanying drawings and the invention resides in certain novel features which will be particularly pointed out in the claims following the description.

In the drawings:

Figure 1 is a perspective view of an embodiment of the invention showing the bracket in place with some parts omitted for the sake of clearness;

Fig. 2 is an enlarged perspective view of the bracket with the curtain supports detached but approximately in their proper relative positions;

Fig. 3 is a longitudinal section on the line 3—3 of Fig. 2;

Fig. 4 is a similar view on the line 4—4 of Fig. 2;

Fig. 5 is a perspective view of part of the clamping means whereby the bracket is secured in position;

Fig. 6 is a perspective view of one of the brackets for supporting the window shade.

In carrying out my invention, I employ a base plate 1 which is provided at one end in its upper portion with a rearwardly extending lip or lug 2 and as the base plate will preferably be constructed of sheet metal in order to avoid undue weight, a re-

inforcing rib 3 is provided on the exterior surface of the base plate which extends around the said lug or lip 2, as clearly shown in Figs. 2 and 4. A longitudinal slot 4 is formed in the base plate substantially in alignment with the said rib to accommodate a perforated ear 5 projecting laterally from the inner end of an arm 6 which, when the parts are assembled, will be disposed at the rear of the base plate between the same and the window frame. At the outer end of this arm 6 is a rearwardly extending lip or lug 7 which is adapted to bear against the outer edge of the window frame in opposition to the lip or lug 2 so that when the arm 6 is shifted longitudinally of the base plate, the opposite vertical edges of the window frame will be clamped and the bracket securely held in place. At the front side of the arm 6 the lug or lip 7 is projected forwardly and provided with an opening 8 to admit an adjusting screw or bolt 9 which is passed through a sleeve or nut 10 formed on the front side of the base plate, the screw or bolt having a threaded engagement with said nut or sleeve, as shown clearly in Fig. 4, so that when the screw or bolt is rotated it will move axially through the nut and carry the clamping lip 7 against the window frame as will be readily understood. The outer end of the screw or bolt is provided with a turning head 11 whereby it may be rotated and this turning head or handle is provided with a face 12 adapted to bear against the outer face of the member 7 so as to force the same inwardly with respect to the base plate. The perforated lug 5 is of such a width that it may pass readily through the slot 4 and at its juncture with the arm 6 is constructed with shoulders 13 whereby a retaining washer 14 will be held against the outer surface of the base plate to bridge the said slot and prevent the accidental or premature withdrawal of the ear through the slot. The said washer is forked or bifurcated, as shown at 15, and the extremities of the forked portion are turned outwardly, as shown at 16, to provide hooks which will engage against the said ear and prevent separation of the parts. The inner extremity 16' of the clamping screw or bolt is reduced and is smooth so that it may rotate easily in the ear 5. When it is desired to remove the bracket from the window frame, the head or handle 11 is rotated so that the screw or bolt will move outwardly

through the sleeve or nut 10 and will permit the arm 6 with the parts mounted thereon to move longitudinally of the base plate so that the clamping jaw 7 will be 5 separated from the edge of the window frame and permit the bracket to be taken down.

The upper portion of the base plate is constructed with a longitudinal slot 17 which 10 extends nearly the full length of the base plate and provides for the adjustment of the window shade bracket 18. The said bracket or holder comprises a forwardly projecting holding arm 19 having an opening 20 at its 15 extremity to receive the pintle of the window shade roller and at its rear end the said holding arm is reduced to extend through the slot 17 and in advance of the reduced portion is merged into the outer clamping 20 plate 21, the inner clamping plate 22 being preferably formed integral with the end of the standard, as shown clearly in Fig. 3, and being further provided with a longitudinal rib 23 which is adapted to fit in the 25 slot 17 so that the holder will be prevented from twisting relative to the slot and will be guided in its movements. The clamping plates 21 and 22 are of such width that they will readily engage the front and rear faces 30 of the base plate at the sides of the slot 17 so that when pressure is exerted upon the said plates they will clamp the base plate and secure the holder in a set position. To apply the requisite pressure to the holder, a 35 screw 24 is mounted in the inner clamping plate and extends through the slot 17 and the outer clamping plate to receive a nut 25 which may be turned home against the outer clamping plate so as to bind it against 40 the base plate. A vertically disposed rib 26 is provided on the front face of the upper portion of the base plate at the inner extremity of the same so as to prevent buckling thereof and a similar lug or rib 27 is 45 provided at the opposite end of the base plate, the latter rib or lug being constructed with a socket 28 opening through the front of the said lug and having its side edges 29 overhanging the interior of the 50 socket, as shown. This socket 28 is intended to receive a tenon or tongue 30 at the inner end of a curtain-carrying arm 31, the said tenon or tongue being suitably shaped to engage behind the overhanging walls 29 of 55 the slot 28 so that the said bracket or curtain-holding arm will be supported upon the base plate and preventing from dropping therefrom. This bracket 31 is provided on its upper edge, near its forward end, with 60 a vertically disposed pin or tooth 32 adapted to pass through an opening in a straight curtain rod 33 and the forward extremity of the said curtain-holding arm is turned upwardly and inwardly, as shown at 34, to 65 provide a hook which will prevent the rod

rolling from the arm if the said pin should be broken. This hook 34 also imparts an ornamental finish to the holding arm so that it adds to the attractiveness of the device. Disposed at the inner side of the rib 27 on 70 the front face of the base plate and immediately adjacent the end of the slot 17 I provide the retaining ribs 35 and 36, the rib 36 being conveniently formed upon the side of the lug 27, as clearly shown. The rib 35 75 is formed on or secured upon the base plate and on its side opposed to the rib 36 is provided with a rib 37 which converges downwardly to the said rib 36 whereby a recess is formed between the ribs and the front 80 face of the plate to receive and support a curved curtain rod 38. The said rod 38 has its ends turned inwardly, and at its extremities is provided with the lateral lips 39 which are adapted to engage behind the ribs 36 and 37 as will be readily understood. Inasmuch as the latter ribs converge downwardly the curtain rod will tend to bind between them and will, therefore, be prevented 85 from dropping so that the rod and the curtains thereon will be properly supported.

It is thought the manner of using the device will be readily understood. The clamping lips or jaws 2 and 7 are so relatively adjusted that they may be disposed at the side 9 edges of the window frame, after which the screw 9 is turned so that the member 7 will be carried to and against the window frame whereupon continual rotation against the screw or bolt will effectually clamp the base 1 plate in position. To prevent marring of the surface of the window frame pads of felt, rubber or other cushioning material, indicated at 39, may be interposed between the clamping jaws and the window frame as 1 will be readily understood. The shade roller will next have its pintles engaged in the openings in the ends of the holding arms 19, the shade holders being adjusted longitudinally of the slots 17 to properly center 1 the shade with respect to the window, after which the nuts 25 are turned home so that the clamping plates 21 and 22 will be caused to bind firmly upon the base plate on the bracket. Upon reference to Fig. 6, it will 1 be noted that the rear face of the clamping plate 21 is provided with a longitudinal groove 40 to accommodate the rib 23. This groove is advantageous inasmuch as it permits the rib to project beyond the front face 1 of the base plate of the bracket so that the edge portions of the clamping plates 21 and 22 will obtain a firm binding engagement with the base plate above and below the slot 17. The curtains will be hung upon the rod 38 and the ends of the said rod then engaged between the ribs 36 and 37, the rod being thus secured in position and the curtains so disposed that when they are properly draped the base plate with the parts

disposed on the front faces thereof will be effectually hidden. A second pair of curtains or a valance may be draped upon the straight rod 33 and said rod then engaged 5 upon the holding arms 31 which will be fitted in the lugs 27 and when the valance or the second pair of curtains has been properly draped the hiding of the brackets will be complete. It will be readily seen from 10 what has been said that I have provided an exceedingly simple device which may be secured in position upon a window frame without the use of any nails, screws, or other pointed fastenings which may mar or damage the woodwork of a window frame. The device may be readily adjusted to the dimensions of any window frame and may be 15 easily and quickly secured in place by an unskilled person. The shade and the curtains will all be carried by the same support and compactness in their arrangement thereby attained and the proper placing of the shade and the curtains upon the window will be facilitated and the curtains supported in such a manner that they cannot 20 catch in nor interfere with the shade as the same is raised or lowered.

Having thus described my invention, what is claimed as new is:

- 30 1. A device for the purpose set forth comprising a base plate having a rearwardly projecting clamping member at one end and having a longitudinal slot near its opposite end, a cut on the front face of the base 35 plate in alignment with said slot, a coöperating clamping member, an arm extending from said clamping member in rear of the base plate and provided with a forwardly projecting ear extending through said slot, 40 a washer engaging said ear but fitting between the same and the base plate to bridge the slot, and an adjusting screw rotatably engaged in the said ear and having a threaded engagement with said nut.
- 45 2. In a device for the purpose set forth, the combination of a base plate, means for

clamping the same upon a window frame, the base plate being provided with a longitudinal slot in its upper portion, a window shade holder comprising clamping plates 50 disposed in front and in rear of the base plate, one of said plates being provided with a rib to fit within the said slot of the base plate, a carrying arm projecting from the said clamping plates, and means for clamping said plates together and against the base plate.

3. In a device for the purpose set forth, the combination of a base plate, means mounted on the lower portion of the base 60 plate to clamp the same upon a window frame, ribs mounted on the front face of the base plate above said clamping means in spaced relation to each other and to the base plate, said ribs converging downwardly, and 65 a curtain rod provided at its extremity with lateral lips adapted to engage behind said ribs.

4. In a device for the purpose set forth, the combination of a base plate, means 70 mounted on the lower portion of the base plate to clamp the same upon a window frame, a vertically disposed rib at the end of the base plate on the front face thereof above said clamping means, said rib being 75 provided with a slot in its upper portion, and a curtain rod supporting arm having its rear end constructed to engage said socket and provided on its upper edge near its front end with an upstanding pin.

5. In a device for the purpose set forth, the combination of a base plate, means on the lower portion of the base plate to clamp the same upon a window frame, and a curtain supporting arm constructed to engage 85 the base plate above the clamping means and provided at its front extremity with an upwardly extending hook and on its upper edge immediately in rear of said hook with an upstanding pin.

In testimony wherof I affix my signature.
NAZAIRE THERIAULT. [L.S.]
